UNITED STATES PATENT OFFICE.

MARTIN HARDSCOG, OF OTTUMWA, IOWA.

DRILL.

No. 923,513.

Specification of Letters Patent.

Patented June 1, 1909.

Application filed May 5, 1908. Serial No. 430,952.

To all whom it may concern:

Be it known that I, MARTIN HARDSCOG, a citizen of the United States, residing at Ottumwa, in the county of Wapello and 5 State of Iowa, have invented certain new and useful Improvements in Drills, of which the following is a specification.

It is desirable, in the operation of drills, for rock and other similar boring, to furnish a 10 medium under pressure for keeping the bits or cutters clear of the cuttings, dust and dirt, so that the cutters or bits can do the work more effectually; and it is also desirable, in the operation of such drills, to give a lead 15 or bearing point by which the drill proper can be made to operate so as to produce overlapping holes by which a clean cut or separation is made in the material being acted upon; and it is further desirable, in such drills, to 20 have the cutters or bits detachable, so that, as the outer corner or edge becomes worn, the cutter or bit can be turned or reversed and present a full corner or edge for use.

The object of the present invention is to 25 construct a drill head carrying cutters and a center or lead bit by which the results, above pointed out as desirable, can be attained in a practical and successful manner.

The invention consists in the features of 30 construction and combinations of parts hereinafter described and pointed out in the claims as new.

In the drawings Figure 1 is a side elevation 35 of the drill, with the several elements entering into its construction assembled ready for use; Fig. 2 a sectional elevation of the drill shown in Fig. 1; Fig. 3 an end elevation of the drill shown in Fig. 1; Fig. 4 a sectional elevation broken off, and taken crosswise to 40 the elevation of Fig. 2; and Fig. 5 a detail in perspective of a detachable cutter or bit.

The head of the drill is made of steel or other suitable material, and consists of a center 1, and wings 2 opposite each other and 45 separated, one from the other, by grooves or passages 3, so as to furnish a clearance on opposite sides of the drill head for the removal of the cuttings, dust and dirt produced in the drilling operation.

50 The base or rear end of the drill head has a threaded hole 4 continuing from which is a chamber 5; and from the chamber 5 a passage 6 leads forward. The passage 6 has leading therefrom opposite lateral passages 7, each 55 passage 7 opening through the outer face of the respective wings; and the outer end of

each passage is closed by a plug 8, which construction enables the lateral passages to be bored transversely through the wings of the head. Each lateral passage 7 has, forwardly 60 leading therefrom, a passage 9, and each passage 9, at the acting end of the drill head, terminates in an enlarged opening or mouth 10, so as to permit the free discharge of a medium under pressure at the acting end of 65 the drill for removing the cuttings, dust and dirt to maintain the cutters or bits clear, the removed cuttings, dust and dirt passing rearwardly, through the grooves or channels 3, with the medium under pressure. 70

Each wing 2, at the acting end, between the side edge or face of the wing and the opening 10, has formed thereon a crosshead or lip lug 11, extending inwardly from the periphery of the wing, and at the center of the 75 body 1 of the drill head is formed a hole 12, leading rearwardly from which is a hole 13 joining the hole or passage 6, as clearly shown in Fig. 2. The wall of the hole or passage 13, at its bottom or rear end, is provided with a 80 screw thread 14 to receive the threaded end 15 of a bit or drill stem or stock 16; and the drill stem or stock has its body reduced in size so as to furnish a neck 17, with a clearance between the neck and the wall of the 85 hole or passage 13, when the drill stem or stock is entered into position. The forward or acting end of the drill stem or stock has a head 18 of a greater diameter in cross section than the neck, so as to furnish a shoulder or 90 abutment 19 between the neck 17 and the head 18, as shown in Figs. 1 and 2. The head or acting end of the center or lead drill is cut away on one side, so as to form a flat face 20; and the terminal end of the drill, at 95 the end of the flat face 20, is cut on a diagonal line, so as to form an inclined face 21, by which a cutting edge 22 is furnished in conjunction with a curved face 23 on the side of the drill head opposite the flat face 20, as 100 shown in Figs. 2 and 3. A hole or passage 24 extends longitudinally through the drill stem or stock, and this hole or passage 24 is in communication with the hole or passage 6, so as to discharge a medium under pressure to 105 clear away the cuttings, dust and dirt at the acting end of the center or lead drill. The medium under pressure is supplied to the passage 6 by means of a suitable supply pipe, not shown, leading from a source of supply, 110 as usual in operating drills in conjunction with a medium under pressure.

The construction shown, at the acting end of the drill head proper, has four cutters or bits. Each cutter or bit has a body 25 with a cutting edge 26, and at each end of the body, on the bottom, is a lug 27 with a recess 28 between the lugs, as clearly shown in Fig. 5. Each bit or cutter has its body entered into a recess 29 formed in the lip 11, with the outer lug engaging the exterior of the lip and the inner lug entered into the central opening 12 and lying against the wall of the body 1 around such opening, so that, when inserted, each bit or cutter will be held firmly in its recess 29 by the engagement of the body 25, with the side walls of the recess and the engagement of the lugs as just described. The bits or cutters are held against forward movement by the engagement of the shoulder 19 of the stem or stock of the center or lead drill with the inner end of each cutter, as shown in Figs. 1, 2 and 4. The center or lead drill is entered partly into the hole or passage 13 thereto in the drill head, so that the shoulder 19 will be sufficiently above the end face of the drill head to allow the main cutters or bits to be entered into place, and when the main cutters or bits are entered the stem or stock of the center or lead drill is threaded into position, thus firmly holding the main cutters or bits in place.

The main cutters or bits, when the outer ends or sides have become worn down so as not to be effective in performing the cutting operation, can be reversed, bringing the inner end or side to occupy the outer position, and to do this all that is necessary is to partially withdraw the center or lead drill a sufficient distance to disengage the shoulder 19 from contact with the main cutters or bits, so that each main cutter or bit can be removed and reversed; and when reversed the main cutters or bits can be again secured in place by threading or advancing the center or lead drill, for the shoulder 19 to engage the edge of each main cutter or bit. It will thus be seen that the center or lead drill furnishes an effective and reliable means for securing the main cutters or bits in place on the end of the drill head, and this without interfering with the operation of the center or lead drill as a drill.

In use, as the drill head, with the center or lead drill in position, is advanced the center or lead drill will first act and form a hole, so that the center or lead drill furnishes a guide and bearing by which the main drill head, with the main cutters or bits thereon, will be held effectively in position to operate, and will be guided by the advance of the center or lead drill in a direct line. The center or lead drill acts as a bearing and retaining point for the main drill head, and its cutters or bits, by which the main drill head with its cutters or bits can be operated to drill overlapping holes, thus removing the material in a con-

tinuous line and enabling the drill to make a clear cut by which a block or section of material can be removed, without the use of any other tool than the drill itself.

It will be understood that the main drill head can be of other shape than one having two opposite wings, so long as the shape is of a nature to furnish an acting end carrying a main cutter or bit; and that, instead of having the main cutters or bits removable, such cutters or bits could be formed integral or permanent with the acting end of the main drill head, and this without departing from the feature of construction in which a center or lead bit acts in advance of the main cutter or bit, so as to furnish a bearing for setting and holding the main drill head and its bits or cutters in position to drill overlapping holes or otherwise. The use of detachable blades or cutters enables a worn out blade or cutter to be removed to be thrown away and replaced by a new blade or cutter; and also enables a dull blade or cutter to be taken out and resharpened, either operation being easily performed by simply withdrawing the center or lead drill a sufficient distance to remove and replace the cutters or blades, and after replacing again advancing the center or lead drill into locking position. The center or lead drill can also be removed for resharpening or replacing a worn out drill or bit.

What I claim as new and desire to secure by Letters Patent is:

1. In a drill, the combination of a drill head having opposite wings of segmental formation extending longitudinally of the head and opposite longitudinal channels between the wings, each wing having therein a longitudinal passage for a medium under pressure, said passage having a discharge mouth at the acting end of the wing, the drill head further having in its center a hole or passage, a plurality of detachable cutters, each provided with an inner lug entered into the central hole or passage, and a central or lead drill provided with a shoulder or abutment and entered into the central passage in position to bring the shoulder or abutment into engagement with the inner ends of the detachable cutters for clamping the same in place, substantially as described.

2. In a drill, the combination of a drill head having opposite wings of segmental formation extending longitudinally of the head and opposite longitudinal channels between the wings, each wing having therein a longitudinal passage for a medium under pressure, said passage having a discharge mouth at the acting end of the wing, the drill head further having in its center a hole or passage, a plurality of detachable cutters, each provided with an inner lug entered into the central hole or passage, and an outer lug engaging the outer face of the drill head, and a center or lead drill entered into the central hole or

passage and provided with a shoulder or abutment adapted to engage the inner ends of the detachable cutters for clamping the same in place, substantially as described.

movable cutters set within the channels and provided with inner lugs for engagement with the drill head, outer lugs on the cutters for engaging the outer ends of the cross heads, and a central lead bit provided with an abutment adapted to engage the inner ends of the cutters for clamping the same in position, substantially as described. 55

5 3. In a drill, the combination of a drill head having oppositely disposed wings of segmental formation and intermediate channels between the wings, the drill head being provided with a central hole or passage radially.

6. In a drill, the combination of a drill

10 arranged cross heads formed on the acting face of the drill head, each of the cross heads being provided with a groove or channel, removable cutters set within the channels and provided with inner lucas for engagement with

6. In a drill, the combination of a drill

15. provided with inner lugs for engagement with the drill head, and a lead bit provided with a shoulder or abutment adapted to engage the inner ends of the removable cutters for clamping the same in place, substantially as described.

6. In a drill, the combination of a drill

20 4. In a drill, the combination of a drill head having oppositely disposed wings of segmental formation and intermediate channels between the wings, each of the wings having formed therein a longitudinally ex-
25 tending passage opening laterally.

6. In a drill, the combination of a drill

25 tending passage opening through the acting face of the wing, the drill head being provided with a central hole or passage, radially arranged cross heads formed on the acting face of the drill head, each of the cross heads 30 being provided with a groove or channel, re-

6. In a drill, the combination of a drill

being provided with a groove or channel, removable cutters set within the channels and provided with inner lugs for engagement with the drill head, and a lead bit provided with a shoulder or abutment adapted to engage

6. In a drill, the combination of a drill

35 the inner ends of the removable cutters for clamping the same in place, substantially as described.

6. In a drill, the combination of a drill

5. In a drill, the combination of a drill head having oppositely disposed wings of segmental formation and intermediate channels between the wings, each of the wings having formed therein a longitudinally extending passage opening through the acting

6. In a drill, the combination of a drill

face of the wing, the drill head being provided with a central hole or passage, radially arranged cross heads formed on the acting face of the drill head, each of the cross heads being provided with a groove or channel, re-

6. In a drill, the combination of a drill
